No. 709,356.

Patented Sept. 16, 1902.

J. W. PIPER.

GAS BURNER.

(Application filed Jan. 23, 1902.)

(No Model.)

UNITED STATES PATENT OFFICE.

JAMES W. PIPER, OF WALTHAM, MASSACHUSETTS.

GAS-BURNER.

SPECIFICATION forming part of Letters Patent No. 709,356, dated September 16, 1902.

Application filed January 23, 1902. Serial No. 90,974. (No model.)

To all whom it may concern:

Be it known that I, JAMES W. PIPER, a citizen of the United States, residing at Waltham, in the county of Middlesex and State of Massachusetts, have invented certain new and useful Improvements in Gas-Burners; and I do declare the following to be a full, clear, and exact description of the invention, such as will enable others skilled in the art to 10 which it appertains to make and use the same.

This invention relates to improvements in gas-burners.

The object of the invention is to provide a combined burner-tube and pilot-light which 15 may be detached whenever it may be desired to substitute a regular burner-tube therefor.

With this and other objects in view, which will readily appear as the nature of the invention is better understood, the same consists in certain novel features of construction and combination and arrangement of parts, which will be hereinafter fully described, defined in the appended claim, and illustrated in the accompanying drawings, in 25 which—

Figure 1 is a top plan view of a gas-burner embodying my invention. Fig. 2 is a longitudinal section on the line 2 2 of Fig. 1. Fig. 3 is a transverse section on line 3 3 of Fig. 1. 30 Figs. 4 and 5 are side views of the distributing-tube and one of the burner-tubes. Fig. 6 is a sectional view showing the substitution of a regular burner-tube for the pilot-light.

The burner is primarily designed for use 35 upon steam-propelled automobiles, but is susceptible of general use wherever a gas-burner is applicable.

Referring now more particularly to the drawings, the numeral 1 represents an air 40 and gas supply pipe, and 2 a distributing pipe or tube open at one end for the reception of the pipe 1 and closed at its opposite end.

Detachably mounted upon the tube 2 are a series of burner-tubes 3, which cross or extend 45 at right angles to said tube 2 and transversely to the general direction of length of the burner. These tubes 3 and the tube 1 are formed with matching recesses, (denoted 4 and 5, respectively,) which serve as ports or 50 passages through which the air and gas from the distributing-tube 1 pass into the several burner-tubes 3 for consumption. The recesses

5 in the tube 1 also form seats for the tubes 3, the side walls of said recesses holding the latter-named tubes in parallel relation. A 55 bolt 6 passes downward through each pipe 3 and the pipe 1 and has applied thereto a nut 7, said bolt and nut detachably securing said pipe 3 and holding it seated in the recess 5. Each tube 3 is provided in its top with one or 60 more longitudinal rows of jet-orifices 8 and has extending therethrough any desired number of vertical tubes 9, forming passages for the upflow of air from below. Surrounding the upper end of each of these passages is an 65 annular row of minute jet-orifices 10. The air from the passages 9 commingles with the jets of gas issuing from the orifices 10, thus promoting combustion. It will be seen that by simply detaching the bolt 6 each tube may 70 be quickly and conveniently removed for cleaning or repairs or the substitution of a new tube therefor. This detachable connection also permits of the use of different forms and sizes of tubes in connection with the pipe 75 1. The drawings show the tubes 3 decreasing in length from the center to each end of the burner to give the burner an elliptical form in general outline; but the burner may be made of any desired general form to correspond to any style of fire-box.

The transverse tube 3^a at the inlet end of the burner differs from the other tubes 3 in that it is not in communication with the tube 1, but is adapted to be supplied with gas 85 through a supply-pipe 11, said tube 3^a thus being constructed to serve as a combined burner-tube and pilot-light. This construction is preferably employed when the burner is used on automobiles and in other relations 90 where it is desirable at certain times to cut off the greater portion of the heat and to merely leave sufficient flame to keep the water in the boiler heated and to light the other burners again when needed. Such a contingency arises in the use of a steam-propelled automobile when it is desired to reduce or 95 arrest the generation of steam while the vehicle is at rest and at the same time to keep the water in the boiler hot and secure the 100 full heat from the burner within a minimum period when the time arrives to again put the vehicle in motion. By cutting off the supply of gas to the distributing-tube 1 the

burner-tubes 3 will be thrown out of operation without affecting the tube 3^a, which will supply enough heat to keep the water in the boiler heated to the proper temperature and 5 at the same time supply a flame to start the burner-tubes 3 when the flow of gas to the tube 1 is again started. If it be desired to extinguish the pilot-light without extinguishing the flame from the burners, this may be 10 accomplished by cutting off the gas from the pipe 11. As shown in Fig. 6, however, a regular form of burner-tube 3 may be substituted for the tube 3^a when it is not desired to employ a pilot-light attachment. The two 15 tubes 3 3^a are interchangeable and the detachable fastening permits of their ready application and removal at will.

From the foregoing description, taken in connection with the accompanying drawings, 20 the construction and mode of operation of the invention will be readily understood, and it will be seen that a burner possessing desirable and important advantages is provided.

While the preferred embodiment of the invention is as herein shown and described, various changes in the form, proportion, and 25

minor details of construction may be resorted to without departing from the spirit or sacrificing any of the advantages of the invention.

Having thus described my invention, what 30 I claim, and desire to secure by Letters Patent, is—

A gas-burner comprising a distributing tube and one or more transverse burner-tubes superposed upon the distributing-tube, said 35 distributing and burner tubes being formed with matching segmental recesses, the recesses in the distributing-tube forming seats for the burner-tubes, each burner-tube having a longitudinal row of perforations, vertical air-passages and an annular row of jet-orifices around said passages, and fastenings 40 detachably connecting the burner-tubes to the distributing-tube, substantially as described.

In testimony whereof I have hereunto set my hand in presence of two subscribing witnesses.

JAMES W. PIPER.
